DISPOSABLE TYPE UMBRELLA

Blanch Poston, New York, and Jerome Bell, White Plains, N. Y.

Application June 6, 1949, Serial No. 97,346

11 Claims. (Cl. 135—20)

This invention relates to an umbrella and more particularly to a disposable type umbrella.

The weather being at least to some degree unpredictable it often happens that what is fair weather when one starts out in the morning is rain in the latter part of the day, and some type of rain protection is necessary. It is for such a case as this, when one comes out of the office, theater, train, or store, that the present invention is disclosed, that is, to have available to a person who is caught unaware, or who does not like to carry a regular umbrella throughout a day that may or may not be stormy, an umbrella at a price of less than the cost of having their clothes pressed which will give them adequate protection to enable them to reach their destination, and which can be dispensed by a machine, or over the counter, or by a concessionaire.

It is an object of this invention to provide an umbrella which is relatively cheap to manufacture, and is of such construction that it can be dispensed in a machine, over the counter, or by a concessionaire at a low cost to the individual, and which will afford adequate protection against a reasonable amount of rain or snow.

Further objects of this invention are to provide a disposable type of umbrella which is encased in a compact container, and which can be readily opened-up; to provide a disposable type umbrella which is contained in a tube which is attractive in appearance and which can be carried easily; to provide a relatively cheap umbrella which can be easily assembled and disassembled and which will provide emergency protection from storm for a few times, and then disposed of without any substantial loss; to provide an improved umbrella of the type described.

In the present form of our invention there is a canopy of a low cost material which is capable of withstanding a reasonable amount of rain. Attached to the canopy are a plurality of ribs, the canopy is attached to a cap which is adapted to be inserted into a handle and has a portion overlying the handle which holds the ribs and canopy in extended position. The umbrella is received by the consumer with the canopy positioned in a tube, the tube serving as a handle when the umbrella is in service. When the canopy is enclosed in the tube the ribs lie against the inner wall of the tube, and to assemble the umbrella, the canopy first is withdrawn from the tube, and the cap is then inserted into the tube, the canopy is then fared out, and cords which are attached to the ribs positioned on the tube. These cords restrain the canopy from being blown inside out by the wind. To collapse the umbrella, the cords are disengaged from the side of the tube, and the cap is withdrawn from the tube, and the canopy folded with the ribs remaining on the outside. This bundle is then inserted into the tube.

Our invention is clearly defined in the appended claims. In the claims, as well as in the description, parts are at times identified by specific names for clarity and convenience, but such nomenclature is to be understood as having the broadest meaning consistent with the context and with the concept of our invention as distinguished from the pertinent prior art. The best form in which we have contemplated applying our invention is illustrated in the accompanying drawings forming part of this specification, in which:

Fig. 1 is a bottom plan view of the umbrella.

Fig. 2 is a vertical section through the umbrella on line 2—2 of Fig. 1.

Fig. 3 is an elevation showing the folded canopy partially inserted in the tube.

2

Fig. 4 is a fragmentary elevation showing an alternate form of retaining means for the cords.

Fig. 5 is a fragmentary section showing a more detailed construction of the cap.

5 Referring now to the drawings, the canopy 10 is constructed of a circular sheet of thin water resistant material. We have found that a thin sheet of plastic is preferable, although paper or cloth may be used. The material chosen should be capable of withstanding a reasonable amount of 10 rain, wind or snow, and also capable of being folded into a compact bundle 13 when not in use, as shown in Fig. 3.

A plurality of ribs 11 are attached to the underside of the canopy 10. In the form shown eight ribs have been used, and they are radially disposed from the center 12 of the canopy 10; however, a lesser number of ribs 15 may be utilized. The ribs are formed of thin cylindrical rods, and preferably constructed of bamboo or other type of wood capable of holding the canopy 10 in extended position. The ribs 11 are attached to the canopy in any 20 conventional manner, and in the form shown have been attached to the canopy 10 by a plurality of tapes 14 which are located on each rib, one adjacent to the periphery 18, another midway between the center 12 and the periphery 18, and a third adjacent the inner end. A washer 15 25 formed of tape or material is located at the center 12 on the top side of the canopy 10. The washer 15 prevents puncture of the canopy from the inner ends of the ribs, and also reinforces the canopy at this point.

A cylindrical cap 16 is attached to the canopy 10. One 30 method of attaching the cap 16 to the canopy 10 is shown in Fig. 5, wherein there is a button 17, knot or other similar object disposed in the washer 15. String 19 depending through the cap 16 is attached to the bottom 20 of the cap 16, but any other conventional means may be utilized.

35 Adjacent to the ribs 11 when the canopy 10 is extended the cap has a portion 21, or disc, which is of a larger diameter than the remainder of the cap 23. This disc 21 overlies the plug 23. This disc 21 being of a substantially greater diameter than the cap 16, acts to position the ribs 40 and canopy in relation to the handle when the umbrella is opened, that is, with the canopy being affixed to the cap 16 the canopy is restrained in movement, and the flange created by the disc 21 holds the ribs in an extended position prohibiting them from converging too greatly. Since the ribs 11 are formed of rods capable of holding the canopy 10 in extended position no braces that are normally found in an ordinary umbrella are necessary; however, to prevent the canopy 10 from being turned inside out by a wind, restraining cords 25 depend obliquely from the mid- 45 portion of the ribs to handle 24. These cords 25 may be formed from string, one being attached to two ribs (not successive) and another similarly attached on the opposite side of the canopy, as shown in Fig. 1. The cords are attached to the handle as will be subsequently disclosed.

50 A hollow cylindrical handle 24 is adapted to receive the plug 23 of the cap 16 and to secure it by frictional engagement. The handle 24 may be formed of a cardboard mailing tube. The handle 24 is cut to provide slits 26, 26 or tabs 27, 27. These slits 26, 26 are utilized to receive and 55 hold the cords 25. The cords 25 are inserted under the slits 26, 26 and the slits then pressed down over the cords, this holds the cords secure, and prevents the canopy from being turned inside out. Rings or hooks (not shown) may be used instead of the slits 26, 26 to hold the cords.

60 The canopy and ribs are capable of being folded into a bundle, and this is insertable into the handle 24, as shown in Fig. 3. The disc 21 prevents the entry of the plug 23 of the cap 16. The handle may be painted or decorated to give it an attractive appearance.

65 When the purchaser receives the umbrella, the canopy and ribs are inserted in the handle forming a compact package, and it may be dispensed by a machine or over the counter. To open the umbrella, the cap 16 is grasped and extracted from the handle 24. The plug 23 is inserted 70 into the handle 24, and the canopy flared out. To prevent the umbrella, from being turned inside out restraining cords 25 are secured to slits 26, 26 on the handle. The ribs are constructed of materials that are capable of supporting the canopy in extended position, and the disc of the cap 75 positions the ribs in such a manner that they assume a 80 positions the ribs in such a manner that they assume a

position that is approximately horizontal, and keeps the ribs from converging too greatly.

To close the umbrella, the restraining cords 25 are dislodged from the slits 26, 26, the handle is turned upside down and the canopy and ribs folded into a bundle. The cap 16 and the bundle formed by the folded canopy are then extracted from the handle. The bundle is then inserted into the handle, and the disc of the cap restrains the entry of the plug of the cap.

Although the umbrella is constructed of economical materials, it can be used several times with average care. The umbrella is easy to dispense in a machine, over the counter or by a concessionaire, and can be easily opened and closed, and carried.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention.

What we claim is:

1. A disposable type of umbrella, comprising: a canopy formed of a thin circular sheet of water resistant material; a plurality of ribs attached to the underside of the canopy extending radially from the center of the canopy to the periphery of the canopy, the ribs being formed of thin cylindrical rods capable of holding the canopy in extended position; a cap attached to the canopy; a hollow handle, a portion of the cap being adapted to be inserted into the handle and having a portion that extends beyond the handle which positions the cap in relation to the handle, and provides a portion which sustains the ribs in extended position; restraining cords attached to the ribs and depending toward the handle; means on the handle to secure the cords.

2. A disposable type of umbrella, comprising: a foldable canopy formed of a thin circular sheet of water resistant material; a plurality of thin cylindrical ribs attached to one side of the canopy, the ribs being disposed radially from the center of the canopy, the canopy moveable with the ribs to form a bundle, the ribs being disposed about the folded canopy; a cylindrical cap being attached to the center of the canopy, the cap having a portion adjacent to the ribs that is of larger diameter than the remainder of the cap; a hollow cylindrical handle having an inside diameter adapted to receive the smaller diameter portion of the cap; and also being adapted to telescopically receive the bundle formed by the canopy and ribs, the larger portion of the cap restraining the entry of the cap.

3. A disposable type of umbrella, comprising: a canopy formed of a thin circular sheet of water resistant material, a plurality of ribs attached to the underside of the canopy, a cap attached to the canopy and having a portion of substantial diameter adapted to hold the ribs in extended position, a hollow handle adapted to receive a portion of the cap; the canopy and ribs being foldable into a bundle, and the handle adapted to receive the bundle when the canopy and cap have been disengaged from the handle.

4. A disposable type of umbrella, comprising: a foldable canopy formed of a thin circular sheet of water resistant material; a plurality of ribs attached to the under side of the canopy being disposed radially from the center of the canopy, and being formed of thin rods capable of holding the canopy in extended position; a cylindrical cap attached to the canopy, the cap having a cylindrical plug and a disc adjacent to the ribs of substantially greater diameter than the plug of the cap, the disc sustaining the ribs in extended position; a hollow handle adapted to receive a portion of the cap, the disc is

of a greater diameter than the cap and thereby acts as a stop and positions the cap; restraining cords depending obliquely from the ribs; slits in handle being adapted to receive and secure the restraining cords.

5. A disposable type of umbrella, comprising: a foldable canopy formed of a thin circular sheet of water resistant material; a plurality of ribs attached to the underside of the canopy, the ribs being disposed radially from the center of the canopy and being formed of thin rods capable of holding the canopy in extended position; a cylindrical cap attached to the canopy, the cap having a disc of substantial diameter adjacent to the ribs which overlies the remainder of the cap, and which positions the ribs in an extended position; a hollow cylindrical handle adapted to receive a portion of the cap and securely retain it, the disc of the cap positioning it in relation to the handle; a plurality of cords depending from the ribs toward the handle; means located on the handle to secure the cords; the ribs and canopy being foldable into a bundle when the cords are disengaged, and insertable into the handle when the cap is withdrawn from the handle.

6. A disposable type of umbrella, comprising: a canopy formed of water resistant material; a plurality of ribs attached to the underside of the canopy; a cap attached to the center of the underside of the canopy; and a hollow handle, the cap having a disc adjacent to the ribs, the disc being of a substantial diameter and forming a flange against which the ribs lie, the disc thereby retaining the ribs and canopy in extended position, the cap also having a plug, the plug being telescopically engaged in the hollow handle.

7. The disposable type of umbrella as described in claim 6, having cords depending from the ribs, the cords being secured to the handle thereby restraining the canopy from being turned inside out.

8. The disposable type of umbrella as described in claim 6, the canopy being foldable in a direction away from the flange into a bundle with the ribs being located on the outside of the bundle, the bundle being adapted to be inserted into the hollow handle, and the disc restraining the entry of the cap.

9. An umbrella, comprising: a hollow handle; a cap having a plug portion telescopically engaged in the handle, the cap also having a disc portion forming a flange which is of a substantially greater diameter than the handle; a canopy attached to the cap; and a plurality of radially spaced ribs attached to the underside of the canopy, the ribs being positioned against the flange formed by the disc, the canopy thereby being maintained in extended position.

10. An umbrella as described in claim 9, having cords depending from the ribs, the cords being secured to the handle thereby restraining the canopy from being turned inside out.

11. An umbrella comprising: a canopy formed of a thin circular sheet of water resistant material, a plurality of ribs attached to the underside of the canopy, a cylindrical cap affixed to the canopy, the cap having a portion adjacent the ribs which is of a substantially increased diameter, the substantially increased portion of the cap sustaining the ribs in an extended position, a hollow handle receiving a portion of the cap.
